KNIFE AND SCISSORS SHARPENER

Filed Dec. 5, 1942

Inventor

Isaac Wentes,

By W. B. Williamson,
Attorney.

UNITED STATES PATENT OFFICE

2,324,805

KNIFE AND SCISSORS SHARPENER

Isaac Wentz, Philadelphia, Pa.

Application December 5, 1942, Serial No. 468,175

5 Claims. (Cl. 51—80)

My invention relates to a new and useful knife and scissors sharpener and has for one of its objects to provide a device of this character that is simple in construction, strong and durable and exceedingly efficient in operation.

Another object of this invention is to provide a frame having two abrasive wheels removably mounted therein, one of said wheels being held in a predetermined location and the other spring pressed into contact with the first one whereby motion will be transmitted to said second one when the first one is revolved.

Another object of the present invention is to construct the frame in a manner that the sharpener may accommodate either a knife or the blade of a pair of scissors.

A further object of the invention is to provide a reversible crank handle to permit the sharpening of knife and scissors blades of different lengths without interference.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawing forming a part hereof, in which:

Fig. 1 is a rear side elevation of a knife and scissors sharpener constructed in accordance with my invention.

Fig. 2 is an end view thereof.

Fig. 3 is a section on the line 3—3 of Fig. 1.

Fig. 4 is a top plan view of the same.

In carrying out my invention as herein embodied 5 is the sharpener frame of general U-shape in cross section and including a bottom wall 6, front and rear side walls 7 and 8, respectively, and a pair of ears 9 projecting from the upper edges of both side walls and the ears of each pair are spaced apart to provide blades receiving recesses 10.

The bottom wall 6 has apertures 11 for the passage of suitable fastening devices to temporarily fix the sharpener to a work bench or other support, and one of the side walls, as 7, has holes 12 whereby the sharpener may be attached to a bracket which is secured to a support.

The ears 9 have slots 13 substantially parallel to the bottom wall and open at their outer ends, that is, the slots of associated ears of each pair open in opposite directions.

The main shaft 14 and the countershaft 15

each has a collar 16 adjacent one end. A fibre or other suitable relatively soft washer 17 is placed on the shaft in engagement with the collar and then an abrasive wheel 18—19 is mounted on its respective shaft. Another soft or compressible washer 20 is placed against the opposite side of the abrasive wheel and finally all are clamped in place by a nut 21 screwed onto the shaft. The shafts are placed in their respective slots in the ears with metal washers 22 between the collars and the nuts and the contiguous side walls or ears.

The main shaft 14 is normally retained in position in its slots by metal straps or retaining plates 23 each of which has a hole in one end to fit over an end of the shaft and a hole in the opposite end to receive a screw 24 which is threaded into a side wall to hold each plate to the frame. The retaining plates function as bearings for the main shaft when the latter does not snugly fit the slots.

A threaded socket 25 is carried by one end of the main shaft 14 to receive either end of the crank 26 having a long handle 27 and a short handle 28. The short handle is connected to the socket when a short blade is to be sharpened, like that of a penknife but when a longer blade is to be sharpened the crank is reversed and the long handle is attached to the socket.

The countershaft 15 is slidably mounted in its slots and urged towards the main shaft, so the abrasive wheel 19 will engage the abrasive wheel 18, by springs 29. Preferably these springs are comprised of wire and secured to the side walls by anchoring means 30, passing back of guide means 31 on the side walls and engaged in grooves in the protruding ends of the counter shaft. This arrangement causes the abrasive wheel 19 to constantly remain in contact with the wheel 18 even as they wear away.

The upper edges of the frame side walls at the ends adjacent the abrasive wheel 18 are fashioned to provide inclined rests 32 at suitable angles to cause the edge of the blade of a pair of scissors to properly contact the abrasive wheel 18 for sharpening said blade. During the sharpening operations on a blade of a pair of scissors the abrasive wheels are revolved and the blade is moved back and forth longitudinally with the inclined rests 32 as a guide.

In sharpening a knife, the blade is placed in the aperture 10 between the two abrasive wheels and moved back and forth while the wheels are revolved through the medium of the crank. The abrasive wheel 18 transmits motion to the wheel

19 through frictional peripheral contact so the contiguous surfaces are moving in the same direction, preferably upwardly. This action cuts away the necessary metal on both sides of the blade simultaneously to produce a sharp edge and if the blade is inserted a sufficient distance between the abrasive wheels it will be hollow ground.

Of course I do not wish to be limited to the exact details of construction shown and described herein as these may be varied within the scope of the appended claims without departing from the spirit of my invention.

Having described my invention what I claim as new and useful is:

1. A sharpener comprising a frame including upstanding ears on opposite sides thereof, said ears having horizontal open-ended slots, shafts mounted in the slots and extending cross-wise of the frame in parallel relation, retaining plates engaging one of said shafts and attached to the frame, a socket on that shaft which is held by the retaining plates, said socket adapted to receive either end of a crank having handles of different lengths, springs mounted on opposite sides of a frame and engaging the other shaft to urge the latter towards the shaft having the socket thereon, and abrasive wheels clamped to

said shafts with the peripheries of said wheels contacting at a location between the ears.

2. The structure in claim 1 wherein the frame is generally U-shape in cross section providing a bottom wall with apertures and side walls, one of which has holes therein.

3. The structure in claim 1 in combination with inclined rests on the frame adjacent the abrasive wheel on the shaft carrying the socket.

10 4. The structure in claim 1 wherein the shaft that is engaged by the springs has circular grooves to prevent slipping of the springs.

5. A sharpener consisting of a frame including a bottom wall and spaced upstanding side walls,

15 a pair of ears projecting from the upper edge of each side walls and having slots opening in opposite directions, a main shaft mounted in the slots of oppositely located ears, means to retain said main shaft in position, a socket on said shaft 20 to receive a crank, an abrasive wheel secured to said shaft, a countershaft slidably mounted in the slots of the other oppositely located ears, an abrasive wheel secured to said countershaft, and springs anchored on the side walls of the frame 25 and passing behind guides and engaging the ends of the countershaft to urge the second abrasive wheel towards the first wheel to retain the peripheries of said wheels in engagement.

ISAAC WENTES.
